UNITED STATES PATENT OFFICE.

FRANK SNYDER, OF NEW YORK, N. Y.

BELT-TIGHTENER.

SPECIFICATION forming part of Letters Patent No. 257,098, dated April 25, 1882.

Application filed February 3, 1882. (No model.)

To all whom it may concern:

Be it known that I, FRANK SNYDER, a citizen of the United States, residing at New York, in the county and State of New York, have 5 invented new and useful Improvements in Belt-Tighteners, of which the following is a specification.

This invention relates to devices for tightening belts, especially intermediate of their pulleys; and it consists in the combination of a 10 hinged frame carrying a tightening-pulley adapted to engage the belt to be tightened, a rack pivoted to the hinged frame, a pinion engaging the rack, and a stop-pawl for holding 15 the pinion in a fixed position, as hereinafter more fully set forth.

This invention is illustrated in the accompanying drawings, in which Figure 1 is a diagram illustrating the manner of applying the 20 tightener to a belt. Fig. 2 is a side elevation. Fig. 3 is a front view thereof.

Similar letters indicate corresponding parts.

The letter A designates the hinged frame; B, the tightening-pulley; C, the rack; D, the 25 pinion, and E the stop-pawl.

The frame A is arranged adjacent to the belt, to be tightened in such a manner that the pulley B, which is mounted in the frame, may be brought in direct contact with the belt.

30 The rack C is connected to the frame A at one end by a pivot, f, and it engages the pin-

ion D by means of its teeth, the pinion being mounted in a rigid standard, g.

The stop-pawl E engages the teeth of the pinion D to hold the latter in the position to 35 which it may be adjusted; but, if desired, a ratchet-wheel may be fixed to the pinion-shaft to receive the stop-pawl.

In applying the apparatus to use the hinged frame A is swung toward the belt, as by turning the pinion-shaft so as to bring the pulley 40 B in contact therewith, and then the stop-pawl E is thrown in gear, whereby the hinged frame, together with the pulley, is firmly held in any position to which it may be adjusted. 45 The rack C passes through the standard g, and is held in gear by means of a roller, i, arranged in contact with the back thereof.

What I claim as new, and desire to secure by Letters Patent, is—

The combination, substantially as hereinbefore set forth, of the hinged frame carrying the tightening-pulley, the rack pivoted to such frame, the pinion engaging the rack, and the stop-pawl, for the purpose set forth.

In testimony whereof I have hereunto set my hand and seal in the presence of two subscribing witnesses.

FRANK SNYDER. [I. S.]
